UNITED STATES PATENT OFFICE.

WALTER D. WINTON, OF VISALIA, CALIFORNIA.

STAND.

Application filed January 13, 1925. Serial No. 2,159.

To all whom it may concern:

Be it known that I, WALTER D. WINTON, a citizen of the United States, residing at Visalia, in the county of Tulare and State of California, have invented certain new and useful Improvements in a Stand, of which the following is a specification.

This invention relates to new and useful improvements to the class of stands which are used in connection with the supporting of cotton boxes or crates and has for its principal object to provide a stand which will hold a packing box in various positions incident to the packing of the same, means being further provided for weighing the contents of the packed box.

Heretofore in the packing of fruit, the fruit was first gathered and then transported to a packing house where it was packed and weighed and the box finally closed and placed in condition for shipment. This necessitated the loss of considerable time and labor and therefore the present invention contemplates the provision of a means whereby the fruit may be packed, weighed and the box closed at the place where the fruit is gathered.

A further object of the invention is to provide a stand of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a side elevation of my improved stand,

Figure 2 is a vertical sectional view thereof,

Figure 3 is a front elevation of the invention, and

Figure 4 is a perspective view of the improved stand.

In the drawing wherein for the purpose of illustration is shown the preferred embodiment of my invention, the numeral 1 designates generally my improved packing stand and the same comprises a pair of spaced vertical standards 2 and 3 respectively. As the standards are each of the same construction, the description of one

is thought to suffice for the description of both. Each of the supporting standards comprises a substantially inverted U-shaped member which is preferably formed of tubular metal and extending between the arms of each of the inverted U-shaped standards are the upper and lower bracing members 4 and 5 respectively. The standards are supported in spaced relation with respect to each other by means of the lower bracing members 6 and 7 respectively, the spacing member 6 extending between the lower bracing members 5 while the bracing member 7 extends between the rearwardly disposed 70 legs of the inverted U-shaped standards.

Extending between the forward arms of the inverted U-shaped member of the standards 2 and 3 at a point adjacent the bracing member 4 is a horizontal cross bar 8. A similar horizontal cross bar 9 extends between the bracing member 4 at a point adjacent the rearwardly disposed arms of the standards and the bar 9 is adapted to cooperate with the horizontal bar 8 in the manner hereinafter to be more fully described.

An additional bar 10 extends between the standards and has its free ends disposed upwardly as illustrated at 11 and secured to the brace members 4 at a point inwardly from the horizontal cross bar 8, the bar 10 being disposed below the bar 8 in the manner clearly illustrated in Figures 2 and 3 of the drawings. Adapted for cooperation with the bar 10 is the bar 12 and the same extends between the rearwardly disposed arms of the inverted U-shaped members comprising the standards 2 and 3 respectively and the last mentioned bar is arranged above the 95 bar 9 and it is also more clearly illustrated in Figure 2.

An arcuate member of tubular material and designated by the numeral 13 has its free end secured to the crown portion of the standard adjacent the rear portion of the stand and the arcuate member 13 provides a means for carrying a weighing scale designated generally by the numeral 14 which may be of any well known construction, and to which is connected the chains 15 on the free ends of which are arranged the article engaging and supporting hooks 16.

The braces and the several bars are formed substantially of the same material as that used in the construction of the standards, although it is to be understood that

any other material may be substituted therefor.

In use, the stand 1 is placed in position at the place where the fruit is gathered and a box such as is shown at A is placed on the stand in such a manner as to have the same supported at an incline thereby causing the box to rest on the bars 8, 10 and 12 respectively. The horizontal cross bar 8 will engage the forward end of the box and provide a stop therefor whereby the box will be held in position on the stand 1 to facilitate the packing of the fruit which has been gathered therein.

15 After the box has been filled with the fruit, the same is removed from the bars 8, 10 and 12 and placed across the bars 8 and 9 whereby the box is supported in a substantially horizontal position and the rear end abuts bar 12. This construction is shown more clearly in the dotted lines in Figure 1. The weighing of the contents of the box is accomplished by placing the hooks 16 on the free ends of the chains 15 underneath 20 the cleats or strips B which extend transversely across the ends of the box in the manner as shown in Figure 2 of the drawing and the box and the contents thereof will be free of the stand and the exact weight of 25 the box and the contents thereof may be readily ascertained by reading the scale 14. It is of course understood that the weight of the box in which the fruit is packed is initially ascertained so that the net weight 30 of the fruit may be readily known.

35 After the box and the fruit which has been packed therein has been weighed, the same is again placed on the horizontal bars 40 8 and 9 and a top is placed over the box and nailed thereto in the usual manner. A receptacle such as is shown at 17 is arranged on the stand for receiving the supply of

nails which are used in fastening the top to the box.

It will thus be seen from the foregoing 45 description, that a stand has been provided which is especially adapted for use in connection with the packing and weighing of fruit, although the same may be used for other purposes, the simplicity of my improved stand enabling a person to save considerable time and labor in packing and weighing boxes of fruit.

While I have shown the preferred embodiment of my invention, it is to be understood that various changes in the size, shape and arrangement of parts may be resorted to without departing from the spirit of the invention and the scope of the appended 55 60 claim.

Having thus described the invention, what I claim is:—

A stand for supporting a box in an inclined position comprising a pair of inverted U-shaped standards vertically disposed in 65 spaced relation, a front horizontal cross bar extending between the forward portions of the standards and adapted to be abutted by the front of a box supported in the stand, a second horizontal cross bar disposed between the standards adjacent the front thereof, to the rear of the front horizontal cross bar, and below the horizontal plane of said front horizontal cross bar, and adapted to be abutted by the front portion of the bottom 70 75 of the box, and a third horizontal cross bar disposed between the rear portions of the standards above the horizontal plane of the front horizontal cross bar and to the rear of the second horizontal bar for the purpose of supporting the rear portion of the bottom of said box.

In testimony whereof I affix my signature.
WALTER D. WINTON.
